US00D543225S

(12) **United States Design Patent** (10) Patent No.: **US D543,225 S**
Shimizu (45) Date of Patent: **** May 22, 2007**

(54) **VIDEO CAMERA**

(75) Inventor: **Minoru Shimizu**, Tokyo (JP)

(73) Assignee: **Sony Corporation**, Tokyo (JP)

(**) Term: **14 Years**

(21) Appl. No.: **29/226,052**

(22) Filed: **Mar. 24, 2005**

(51) **LOC (8) Cl. 16-05**

(52) **U.S. Cl. D16/219**

(58) **Field of Classification Search** D16/200-205,
D16/208, 218, 219; 348/373-376; 358/906;
396/535-541

See application file for complete search history.

(57) **CLAIM**

The ornamental design for a video camera, as shown and described.

DESCRIPTION

FIG. 1 is a rear perspective view of a video camera showing my new design;

FIG. 2 is a right side elevational view thereof;

FIG. 3 is a rear elevational view thereof, wherein a monitor portion is in a first open position; and,

FIG. 4 is a rear perspective view thereof, wherein the monitor portion is in a second open position.

Portions of FIGS. 1-4 that are shown as broken lines are for illustrative purpose only and form no part of the claimed design.

1 Claim, 4 Drawing Sheets

FIG. 1

FIG. 2

FIG. 3

FIG. 4
